Primary Examiner — Llorellys Martinez-Rivera(74) *Attorney, Agent, or Firm* — Dinsmore & Shohl LLP(57) **CLAIM**

The ornamental design for a cove corner trim, substantially as shown and described.

DESCRIPTION

FIG. 1 is a cross-sectional of a cove corner trim showing our new design; and,

FIG. 2 is a top and left perspective view thereof.

The broken lines in the drawings represent portions of the cove corner trim and form no portion of the claimed design.
